UNITED STATES PATENT OFFICE.

JAMES M. CHAMBERS, OF TWIN FALLS, IDAHO, ASSIGNOR OF TWO-THIRDS TO JOHN M. MAXWELL AND CHARLES O. LONGLEY, BOTH OF TWIN FALLS, IDAHO.

AIR-VALVE.

1,075,332.

Specification of Letters Patent.

Patented Oct. 14, 1913.

Application filed October 15, 1912. Serial No. 725,839.

To all whom it may concern:

Be it known that I, JAMES M. CHAMBERS, a citizen of the United States, residing at Twin Falls, in the county of Twin Falls and State of Idaho, have invented certain new and useful Improvements in Air-Valves, of which the following is a specification.

My invention relates to air valves of the type used on steam boilers or on conduits such as the radiators included in a steam heating system and one of its objects is to provide a device of simple construction which, normally, provides an outlet for air contained in the vessel or conduit with which it is connected and which operates by the heat of steam admitted thereto, to close the said outlet after all the air has escaped and to reopen the same for the purpose of preventing the formation of a partial vacuum, only when by discontinuation of its supply or other causes, the steam contained in the vessel or conduit is reduced in temperature.

Another important object of my invention resides in the provision of means for the drainage of all water of condensation from the valve housing the moment it is formed so that the valve can at no time be rendered inoperative by the presence of a quantity of water in its housing, as often occurs in many of the air valves at present in common use.

With the above objects in view my invention consists briefly, in providing a housing which by means of two separate passages, is connected with the vessel or conduit to which the valve is applied and which has an opening for the escape of air into the atmosphere. A valve disposed to close said opening by its movement in one direction, is mounted to be lifted by the expansion of a body of mercury or other expansive fluid which is contained in a vessel disposed within the housing in spaced relation to its wall.

The steam entering the housing and filling the space around the vessel, heats the latter and causes the expansion of the fluid contained therein, which in consequence lifts the valve to its closing position with relation to the air outlet. The parts remain in this position until by a decrease in the temperature of the steam, the vessel is cooled and its contents are contracted when the valve, impelled by gravity will reassume its normal

position and reopen the outlet for either the escape of air into the atmosphere or for the admission of air to destroy a partial vacuum that may form by the condensation of steam as the system cools. The lower one 60 of the two passages above referred to, connects the bottom portion of the housing with the radiator for the discharge of water of condensation.

An embodiment of my invention as outlined above, is shown in the accompanying drawings in the two views of which like parts are similarly designated and in which,

Figure 1, represents a vertical section through my improved air valve as applied 70 to a radiator of a steam-heating system, and Fig. 2, a vertical section taken along the line 2—2, Fig. 1.

Referring to the drawings by numerical characters, 2 designates the cylindrical valve 75 housing provided with a laterally extending, exteriorly threaded nipple 3 by means of which it is connected to the end section 4 of a radiator. A vertically disposed outlet 5 at the lowermost point of the concave bottom portion of the housing, as an exterior screw thread for the application of a nut 6 which has a swivel connection with a curved conduit 7 and serves to produce a steam-tight joint between the latter and the outlet 5. The opposite end of the conduit is threaded and secured in a correspondingly threaded opening formed in the radiator section at a point below that at which the nipple 3 is connected, for the discharge of 85 water of condensation from the valve housing. The open upper end of the housing is closed by means of a screw cap 8 provided with a central opening which is threaded to secure the upper end of a yoke 90 9 which thus is suspended within the housing. The yoke 9 consists of an axially bored stem 10 which at its upper extremity is connected in the opening of the cap, and a circular body portion 12 which is integrally connected with the stem by means 95 of a pair of diametrically opposite arms 13. The open-ended bore 21 of the stem is counter-sunk at its lower end to provide a seat 14 for a conoidal valve 15, the stem 16 100 of which is loosely fitted in a central opening 17 in the body portion 12 of the yoke. The body 12 has at its lower surface, an internally threaded recess into which is secured the upper, correspondingly threaded 110

end of a cylindrical cup 18 which is thus suspended from the yoke in spaced relation to the interior surface of the housing 2. The cup 18 is partially filled with a quantity of mercury or other suitable fluid 22 which when expanded by the influence of heat applied exteriorly of the cup, acts upon a float piston 19 which is secured at the lower end of the valve stem and is loosely fitted in the vessel 18.

The valve when in its normal position, in which it is separated from its seat, is suspended from the yoke 9 by means of a disk 20 which being secured at the upper portion 15 of its stem, rests upon the upper surface of the body 12. When the valve is in this position, the piston 19 at the lower end of its stem either rests upon the surface of the fluid in the cup or extends a short distance 20 above the same, it being obvious that the quantity of fluid disposed in the vessel is determined by the degree of temperature of the steam used in the system to which the air valve is applied.

While the parts are in their normal position, as above described, the interior of the valve housing is continuously in communication with the atmosphere through the open-ended bore 21 in the yoke 9 and when at the 30 initial point of operation of the heating system; steam is admitted into the conduits comprised therein, it drives the air before it and through the outlet in the valve until it reaches the last section of the radiator 35 to which the latter is applied when, filling the space between the wall of the housing 2 and the outer surface of the vessel 18, it heats the latter and causes the expansion of the fluid contained therein, which in consequence rises in the cup and lifts the valve until it engages its seat at the lower end of the bore 21 and thus closes the communication 40 between the radiator and the atmosphere. When, subsequently, the steam in the radiator is reduced in temperature either 45 by discontinuation of its supply or other causes, the fluid in the cup is proportionately contracted with the result that its level is lowered and the valve impelled by gravity, 50 is separated from its seat until the disk has again come to rest upon the upper surface of the body portion 12 of the yoke. By thus reestablishing the communication between the interior of the radiator and the atmosphere, the formation of a partial vacuum by 55 condensation of the steam is avoided and the water of condensation formed by the cooling of the steam in the valve housing, is drained therefrom through the conduit 7 and is discharged from the system in the 60 usual manner.

It will be observed that after the fluid in the vessel has commenced to expand, the upward movement of the valve is accelerated 65 by the pressure of the steam against the

lower surface of the disk, thus effecting a substantially instantaneous closing of the outlet 21 and preventing the escape of steam through the same. The provision of the two passages between the radiator and the valve 70 housing, balances the pressure within the latter and thus allows an unobstructed flow of water of condensation through the conduit 7. The valve mechanism being suspended in its entirety from the cap may be readily 75 removed from the housing for the purpose of inspection or repairs and as it is practically impossible to remove the device from the radiator without the use of tools, ignorant or mischievously inclined persons are 80 prevented from detaching the valve from the radiator, and thereby damaging the walls and furniture of rooms in which the radiators are located, as often occurs in hotels, rooming houses and other public places. 85

Having thus described my invention what I claim and desire to secure by Letters-Patent is:

1. An air valve of the character described comprising a housing open at its upper end 90 and having means for the connection of its interior with a radiator or the like, a cover removably connected with the housing to close its open end and having an outlet, a mercury vessel spaced from the interior surface of the housing, a body of mercury in said vessel, a connection by which said vessel is detachably suspended from the cover, and which has a valve seat in communication with said outlet, a valve adapted to engage said valve seat to close the outlet and normally suspended from said connection, and a float disposed in said vessel and connected with said valve to move the same into engagement with the valve seat, when lifted 95 by the expansive action of the said body of mercury.

2. An air valve of the character described comprising a housing open at its upper end 100 and having means for the connection of its interior with a radiator or the like, a cover removably connected with the housing to close its open end and having a central aperture, a yoke connected in the said aperture and having an air-passage extending through the same, a mercury vessel detachably suspended from said yoke in spaced relation to the interior surface of the housing, a valve adapted to control the flow of fluid from the interior of the housing into the said passage 115 by engagement with the mouth thereof, said valve being normally, loosely suspended from said yoke beneath the said mouth, a body of mercury in said vessel, and a float disposed in said vessel and connected with said valve to move the same in engagement 120 with said mouth when lifted by the expansive action of said body of mercury.

3. An air valve of the character described comprising a housing having an aperture 130

and means for the connection of its interior with a radiator or the like, a yoke connected in said aperture and having a passage for the outlet of fluid from the interior of the 5 housing and, opposite to the mouth of said passage, a seat for the suspension of a valve, a valve adapted to close said passage by engagement with its mouth, a disk connected with said valve, and normally resting upon 10 said seat, the said yoke being constructed to admit fluid within the housing, to the said seat for action upon the said disk, a mercury vessel suspended from the yoke in spaced

relation to the interior surface of the housing, a body of mercury in said vessel, and a 15 float in said vessel, connected with said valve for moving the same in engagement with the mouth of said passage, when lifted by expansion of the said body of mercury.

In testimony whereof I have affixed my 20 signature in presence of two witnesses.

JAMES M. CHAMBERS.
